(57) **CLAIM**

The ornamental design for a daylight running light arrangement for a tail light, as shown and described.

DESCRIPTION

FIG. 1 is a front right perspective view of a daylight running light arrangement for a tail light for a vehicle according to the present invention.

FIG. 2 is a front left perspective view of the daylight running light arrangement shown in FIG. 1.

FIG. 3 is a front view thereof.

FIG. 4 is a right side view thereof.

FIG. 5 is a top view thereof.

FIG. 6 is a front view of the daylight running light arrangement shown in FIGS. 1-5, but located on the rear right side of a vehicle, with the rest of the vehicle shown in de-emphasized and half-tone portions so as to illustrate environmental structure.

More particularly, in FIG. 6, the inventive daylight running light arrangement is shown within the broken lines, and the rest of the elements line form no part of the claimed invention, but are instead included to show environmental aspects thereof; and,

FIG. 7 is a front view of the inventive daylight running light arrangement for a tail light according to an alternative embodiment of the invention, namely, with two mirror image arrangements located on both rear sides of a vehicle. In the Figures, the broken lines serve as an unclaimed boundary both inside and outside the closed rectangular shapes. Also, even though the light emitted from a tail light is not dark, in the Figures the emitting portions of the light, i.e., the closed rectangular shapes, are shown as dark, to provide a more effective contrast with the surrounding half-tone environmental portions of the tail light of the vehicle, to enable the design to be more readily visible.
